UNITED STATES PATENT OFFICE.

VICTOR H. COCHRANE, OF TULSA, OKLAHOMA.

SEWER CONSTRUCTION.

Application filed June 18, 1925. Serial No. 38,045.

This invention relates to improvements in sewer constructions.

The primary object of this invention is the provision of a sewer construction, where-
5 by the stresses upon the sewer may be accurately determined.

A further object of this invention is the provision of an improved sewer construction embodying novel means of forming the arch 10 upon the abutment, with hinge joints, so as to do away with uncertain stresses in monolithic construction.

A further object of this invention is the provision of a sewer construction which will 15 materially reduce the quantity of concrete required with certain types of sewer constructions, such as the monolithic construction, and provide in addition a sewer in which the stresses can be foreseen and safely 20 taken care of.

A further object of the invention is the provision of a sewer construction including abutments and an invert independently connected by means of flexible joints, so that the 25 invert is prevented from carrying any part of the load from the arch or abutments, and further providing an arch section attached to abutments by means of joints which are so constructed as to fix the location of the 30 resultant thrust at the center of the arch section at the joint, so that the arch is virtually two-hinged for dead load and fixed or partially fixed for live load.

A further object of this invention is to 35 provide a sewer construction which includes the formation of the abutments, upon which the arch barrel is subsequently supported by means of novel joint constructions which permit hinge action of the arch upon the 40 abutments, thus enabling the arch barrel to adjust itself to the pressure exerted by the filling material thereover, and to the shortening of the axis caused by the compressive stresses.

45 Other objects and advantages of this invention will be apparent during the course of the following detailed description.

In the accompanying drawings, forming a 50 part of this specification, and wherein similar reference characters designate corresponding parts throughout the several views.

55 Figure 1 is a cross sectional view taken through the completely constructed sewer, at a typical cross section, and showing the comparative formation of the same with the

present requirement of monolithic structure of the same size; the monolithic structure being shown in this view in dot and dash lines.

60 Figure 2 is a fragmentary sectional view taken on a horizontal plane substantially on the line 2-2 of Figure 1.

65 Figure 3 is a sectional view taken through an abutment of the sewer construction, showing the first step in the formation of the sewer construction.

70 Figure 4 is a fragmentary sectional view showing the form work at the joint between the arch at its springing edge and the abut-
ment.

75 Figure 5 is a sectional view showing another step in the construction of the arch upon the abutment, by means of which the same has a hinge action thereon during the filling of earth or other material over the arch to permit the arch to settle and adjust itself to the pressure of the dead load.

80 Figure 6 is a fragmentary sectional view showing an alternative form of joint construction.

85 In the drawings, wherein for the purpose of illustration is shown only a preferred construction of the arch and a preferred design of the same, the letter A may generally designate the finished sewer construction, which may consist of the abutments B; arch C; and invert D.

90 In present types of sewer constructions, the stresses may be accurately figured only in case the foundations are firm and un-
yielding, whereas if there should be any settlement or rotation of the arch abutment at its foundation unforeseen stresses may be set up throughout the arch ring. Some 95 sewer constructions to obviate this require the sewer invert, arches and abutments to be made very thick, in a monolithic construction. This is so especially in the case of sewers resting upon soft foundations, in 100 contradistinction to rock foundations. To obviate this factor by increasing the thicknesses of the parts of the sewer is sometimes inconvenient and expensive. To do away with such uncertainty of stresses, the novel 105 sewer construction and method of forming the same herewith set forth has been provided, which will enable all stresses to be accurately determined, and requires the use of only about the same amount of material 110 for a soft foundation, as would be necessary for a rock foundation of present sewer con-

structions. It is extremely economical as compared with forms of sewer construction now in use. In Figure 1 has been given the comparative sizes of sewer constructions 5 according to my method and according to a present known method, in which the latter is illustrated in dot and dash lines.

Prior to the forming of the arch portion C, the abutments B and preferably the invert D are constructed. The abutments B are formed to provide the main body portion 10, which provides an inside wall surface 11 adapted to lie contiguous with the intrados 12^a of the arch C. At the outer side of the body 10 of the abutment B, the abutment extension 12 is provided, of any approved length, providing a foot for distribution of load thrust; the height of this extension 12 between the top surface 13 of the abutment B, and the bottom surface 14 thereof, preferably decreasing towards the outer edge of the extension 12. As a novel feature of the abutment B the same is provided with an invert extension portion 15, providing a toe, 25 so to speak, for the abutment B, which extends at the opposite side of the abutment from the extension 12, and which in reality is a part of the invert of the sewer A. This toe or invert extension 15 is of course considerably reduced in height with respect to the abutment, and it has a top surface 18 adapted to lie contiguous with the invert flow surface and provide part of the same.

The reinforcing of the abutment B plays 30 an important part in the sewer construction, and during the formation of the abutment, the reinforcing rods or bars 20 and 21 are embedded in the cementitious material of the abutment. The rods 20 and 21 are crossed 35 at 24, and preferably held by a ring 25 or analogous element at this point just upwardly of the top surface 13 of the abutment B, and which cross location 24 really lies in the joint space 26 when the arch C is connected to the abutment B, as has been illustrated in Figure 5 of the drawings. The bars 20 and 21 from the cross location 24 extend upwardly in divergent relation, and provide the end portions 28 and 29 adapted 40 to be embedded in the springing portions of the arch C to hingedly connect the arch to the abutments. The reinforcing bars or rods 20 and 21 extend into the abutment B preferably in divergent relation, at portions 30 and 50 31, and the portion 30 may terminate at 32, or it may be arcuated and bent for embedding at a portion 34 extending into the invert or toe extension 18, for reinforcing the same. Additional reinforcing rods 35 may 55 also be provided along the bottom of the abutment throughout the width thereof, as has been illustrated in the drawings.

Inasmuch as the reinforcing bars or rods 60 20 and 21 are in compression, it may be advisable to insert stirrups, ties or thrust dis-

tributing plates 39 and 40 in the abutments B and arch C, adjacent the joint space 26, to prevent cracking of the concrete or cementitious material.

The invert D is separated from the invert 70 extensions 15 of the abutments B, by means of joints 45, which may be any approved flexible or slip construction joint, such as tar paper, or other elastic substance such as asphalt, resting directly on the foundation 75 or held in place by stirrups 46, which at their ends are anchored in the invert and abutment, as is illustrated in Figures 1 and 5 of the drawings. It is to be particularly noted that with such a construction the main 80 invert D does not comprise the entire invert, but the extension 15 may also be considered as included in the term "invert." With this construction the joints 45 are placed much closer to the center line of the sewer, than 85 are invert joints which have heretofore been provided in sewer constructions of proportionate size. With such construction the invert D is made relatively shallow, since it does not support any of the dead load 90 thrusts, and the abutments may move relative thereto without fracturing the invert main section D.

After the abutments have been placed, the joint space 26 is filled preferably with some suitable material that can be removed to permit arch settlement, such as forms made up of detachable wedge pieces 50 and 51. The inner and outer forms of the arch C are of course placed, and the reinforcement 100 53 and 54 adjacent the intrados and extrados sides of the arch are placed, and the concrete is poured and allowed to set in the form provided therefor. After the arch concrete has been sufficiently cured, the forms are removed and the earth or other covering over the arch is placed. If wooden forms have been used in the joint space 26 they are removed either before or after the dead load has been placed, and at this juncture the entire weight 105 of the arch and superposed loads will be concentrated upon the cross locations 24 of the reinforcing rods 20 and 21, at the center of the joint space 26, and as can be readily understood, thus definitely fixing the location of the resultant thrust at these points. After the arch has had time to adjust itself, and the earth fill and the foundations have fully settled, the joint space 26 may be 110 pointed up with any suitable filling material 56, which may be cement or some elastic material, such as asphalt. In lieu of using the wooden forms 50 and 51 to support the arch during its formation, the spaces 26 between the abutments and the arch springing ends might be filled with some elastic substance, as asphalt, which will remain 115 permanently in place. This construction is preferable in the event that it is impracticable to place the full amount of earth fill-

120 125 130

ing on the arch at the time of construction, in which case the layer of elastic material is made as thin as may be, and at the same time to permit of a sufficient amount of rotation of the arch relative to the abutment. To prevent access of water to the reinforcing rods 20 and 21, longitudinally extending metal diaphragms 61 and 62 may be used, at opposite sides of the hinge joints provided by the crossing of said rods, said diaphragms being embedded in both the abutment and arch ring, and providing, in effect, a closed channel, as is illustrated in Figure 6 of the drawings.

As to the steps of construction, the preferred method of forming the sewer is to first form the abutments B and the invert D, and the arch barrel C is subsequently supported in the manner above described upon the hinges formed by the reinforcing rods 20 and 21, or in any other analogous manner which will permit a slight rotational movement at the ends of the arch. The joint spaces are then filled with cement, concrete or other suitable material, such as elastic asphalt, although not until the sewer trench has been back filled and the filling material allowed to settle, and the arch to adjust itself to consequent pressures. If such adjustment cannot be accomplished at the time of construction, the joint filling material is to be of an elastic nature and left in place, being formed on the abutments B before the arch C is built. It is also contemplated to provide other hinge connections not shown specifically by the reinforcing bars 20 and 21.

The advantages of the above method consist essentially in the fixing of the position of the line of thrust at the center of the arch section and concentrating it at joints adjacent to the arch support upon the abutments, so as to permit some relative movement between the arch barrel and abutments, without fracturing the sewer construction, as does actually occur in monolithic sewer construction. It is a fact that with this improved method of sewer construction, the arch and abutments can be made lighter in section and with smaller quantities of reinforcing steel than other sewer constructions of the same size, thus effecting a considerable economy without any decrease in strength.

Thus, briefly, it can be seen that the sewer construction consists of a pair of abutments at each side, an invert section separated by joints from the abutments permitting relative movement so that the abutments may settle independently of each other and the invert, and preventing the invert from carrying part of the load of the arch and abutments; and lastly an arch section attached to the abutments by means of hinge joints which fix the location of the resultant thrust at a place which can receive the same with-

out fracturing any part of the sewer construction. The arch is thus virtually two hinged for dead load and fixed or partially fixed for live loads. An additional advantage is that the improved sewer construction reduces the stresses caused by the arch shortening, so called, as compared with the ordinary monolithic construction.

Various changes in the steps to place the various parts of the sewer construction, shape, size, and arrangement of parts may be made to the invention herein shown, illustrated and described, without departing from the spirit of the invention or the scope of the claims.

I claim:

1. In a sewer construction the combination of abutments having integral invert extensions, a main invert section, means flexibly connecting the main invert section at its ends with said invert extensions of said abutments, and an arch superposed upon said abutments.

2. In a sewer construction the combination of abutments having integral invert extensions, a main invert section, means flexibly connecting the main invert section at its ends with said invert extensions of said abutments, an arch barrel, and yieldable joint means connecting the arch barrel at its springing ends in a leak-proof connection upon said abutments for limited relative movement with respect to said abutments.

3. In a sewer construction the combination of abutments, an arch, reinforcing members embedded in said abutments and in said arch to hingedly connect the arch to said abutments, and diaphragm members longitudinally extending along said abutments and arch embedded therein at opposite sides of each of the joint connections provided by said reinforcing members.

4. In a joint construction a pair of concrete sections, metal reinforcing members each embedded in each of said sections and extending across the joint location between said sections, and flexible metal diaphragm means embedded in each of the sections at each side of the location where the said reinforcing members cross the joint between said sections, to seal the joint location against access of moisture to said reinforcing rods.

5. In a flexible joint construction the combination of a pair of concrete sections, reinforcing rods embedded in each of the sections and extending across the location between said sections whereby to hingedly connect the sections together to permit relative movement thereof, and a metal diaphragm member at each side of the location where the reinforcing rods cross the joint location of said sections, each metal diaphragm member being embedded in each of the sections and crossing the joint location between said

sections to liquid seal the rods at the joint location against access by moisture.

6. In a flexible joint construction the combination of a pair of concrete sections, reinforcing rods embedded in each of the sections and extending across the location between said sections whereby to hingedly connect the sections together to permit relative movement thereof, a metal diaphragm member at each side of the location where the reinforcing rods cross the joint location of said sections, each metal diaphragm member being embedded in each of the sections and crossing the joint location between said sections to liquid seal the rods at the joint location against access by moisture, said flexible diaphragms at the joint location being crimped to facilitate the flexing thereof during relative movement of the concrete sections.

7. In a flexible joint construction the combination of a pair of concrete sections, reinforcing rods embedded in each of the sections and extending across the location between said sections whereby to hingedly connect the sections together to permit relative movement thereof, a metal diaphragm member at each side of the location where the reinforcing rods cross the joint location of said sections, each metal diaphragm member being embedded in each of the sections and crossing the joint location between said sections to liquid seal the rods at the joint location against access by moisture, and sealing material in the joint location between said concrete sections outwardly beyond said diaphragms.

8. In a sewer construction the combination of elongated abutments each including a body portion and a reduced laterally extending invert extension of less height than the body portion, an elongated invert between the invert extensions and in top surface flush relation therewith, flexible joint means connecting and sealing the joints between the longitudinal edges of the invert and the invert extensions of said abutments, a main arch ring, and metal hinge connections embedded in the ends of the arch ring and the body portions of the abutments to mount the springing ends of the arch ring for some relative movement with respect to the abutments.

9. In a sewer construction the combination of elongated abutments each including a body portion and a reduced laterally extending invert extension of less height than the body portion, an elongated invert between the invert extensions and in top surface flush relation therewith, flexible joint means connecting and sealing the joints between the longitudinal edges of the invert and the invert extensions of said abutments, a main arch ring, metal hinge connections embedded in the ends of the arch ring and the body portions of the abutments to mount the springing ends of the arch ring for some relative movement with respect to the abutments, and an elastic non-concrete construction in the joint location between the springing ends of the arch ring and the abutments for sealing and protecting the hinge rods against deteriorating influences.

VICTOR H. COCHRANE.
